YARN GUIDE FOR FULL-FASHIONED
KNITTING MACHINES

Emil William Kaul, Wyomissing, Pa., assignor to
Textile Machine Works, Wyomissing, Pa., a corporation of Pennsylvania

Application May 14, 1949, Serial No. 93,232

7 Claims. (Cl. 66—126)

1

The present invention relates to reciprocating yarn carriers and particularly to those for use in full-fashioned and other types of weft-knitting machines.

As is well known, the yarn carriers in full-fashioned knitting machines are arranged to be reciprocated in a straight line across a bank of needles. In such arrangement each of the carriers is carried upon a separate bar or rod in side by side relation, and in order to bring the delivery ends of the carriers in the same plane, the carriers are bent to various angles. Each of the yarn carriers is so designed that the yarn extends along the upper face thereof, through a groove in the carrier face adjacent to its bend and to and through a guide tube at the lower end of the carrier aligned with said groove. As there may be as many as nine carriers for each knitting section operating to deliver yarn in the limited space between the sinker head cap member and the needles of the machine, all of the carriers have the lower ends thereof bent to conform to the front edge of said cap member with the carriers closest to the cap member having the greatest degree of bend. The carriers having the greatest degree of bend are usually the main carriers and are therefore, used more extensively than the carriers having the least degree of bend. Further, in the carriers having the greatest degree of bend the grooves cannot be made sufficiently deep so that the yarn contacts the bottom surface of the bend in the carrier in passing to the guide tube.

The usual yarn carriers are also provided with replaceable guide tubes which may be readily removed when worn by withdrawing them upwardly from the bores in the lower ends of the carriers, such removal of the tubes being facilitated by the grooves in the carriers.

Usually with this relation of the groove and guide tube few, if any, difficulties arise due to the general run of yarn fed through the carrier. However, the present synthetic yarns of the linear condensation polyamide group, so-called nylon, and particularly of the mono-filament type, which is now in extensive use, in many instances has an abrasive action on the parts of the carrier contacted by the yarn. With this type yarn the abrasive action is particularly damaging to that portion of the groove at the bend of the main carriers, or those having the greatest degree of bend, with the result that the remaining metal at the bend is cut or worn through in a very short time. With the carrier cut through the slightest defect or projection on the yarn snags itself in the cut, consequently tearing the yarn and causing the fabric to be pressed-off.

It is an object of the invention to provide

means on a reciprocating yarn carrier for preventing the yarn from roughening or cutting the grooved portion of the carrier without detracting from the efficiency of the carrier.

5 Another object of the invention is to provide means associated with the yarn carrier for preventing the yarn from entering the groove of the carrier and which may be readily applied to or removed from the carrier without affecting the setting thereof.

10 Another object of the invention is to provide a yarn guard arrangement on a yarn carrier adapted for use with both multi-filament and mono-filament yarns, the guard being free of any corners on which the yarn may catch in operation.

15 It is still another object of the present invention to provide a very light guard means for a reciprocating yarn carrier adapted to prevent abrasion of the carrier by the yarn, whereby the use of the guard means will not materially increase the inertia of the reciprocating parts and therefore will not materially increase the forces developed in the machine during operation.

20 Another object of the invention is to provide a yarn guard arrangement on a yarn carrier having a high economy of manufacture and installation.

25 With these and other objects in view, which will become apparent from the following detailed description of the embodiment of the invention shown in the accompanying drawing, the invention resides in the novel elements, features of construction and combinations of parts in cooperative relationship as more particularly pointed out in the claims.

30 In the drawing:
Figure 1 is a perspective view of a yarn carrier within the invention mounted in a full-fashioned knitting machine together with a fragment of the bar for supporting the carrier and of the knitting mechanism associated therewith;

35 Fig. 2 is a sectional view taken on a vertical plane at right angles to the axis of the bar supporting the carrier shown in Fig. 1 but on a considerably enlarged scale compared to Fig. 1;

40 Fig. 3 is a sectional view taken substantially on the line 3—3 of Fig. 2, looking in the direction of the arrows;

45 Fig. 4 is a view similar to Fig. 3 of a modified form of the invention; and

50 Fig. 5 is a sectional view taken along the line 5—5 of Fig. 4.

55 In the drawing and description, only the means necessary to a complete understanding of the invention are specifically set forth; further information as to the construction and operation of other related, usual and well known knitting machine elements, mechanisms, etc., may be

found in one or more of the following publications:

1. Pamphlet entitled—Full-Fashioned Knitting Machines—published and copyrighted by the Textile Machine Works, Reading, Pennsylvania, in 1920.

2. Four catalogs entitled—“Reading” Full-Fashioned Knitting Machine Parts Catalog—published and copyrighted by the Textile Machine Works, in 1929, 1935, 1940 and 1947, respectively.

3. Booklet entitled—The “Reading” High Production Full-Fashioned Knitting Machine—which, forming a supplement to the above noted 15 1940 parts catalog of the Textile Machine Works, is a publication of the Textile Machine Works, copyrighted by the latter in 1940.

4. Pamphlet entitled—Knitting Machine Lectures—published by the Wyomissing Polytechnic Institute, Wyomissing, Pennsylvania, in 1935.

The arrangement within the invention shown in the drawing is one designed for a full-fashioned knitting machine and comprises a yarn carrier rod or bar to which is fixed a yarn laying means having a plate or holder fixed directly to the bar and having a carrier, in the form of an arm which supports a yarn guide or delivery tube, by which the yarn is delivered to knitting or loop forming elements of the machine. It will be understood that such a bar extends along nearly the full length of the machine and has yarn carriers thereon, one for each knitting section, and that a full-fashioned knitting machine may have as many as thirty or more knitting sections. When the machine is designed to use nine yarns, there are nine carrier rods arranged in a group and reciprocated when desired by connecting them to friction boxes on a friction rod forming part of a coulier mechanism adapted to reciprocate the friction rod during knitting operations of the machine. All the yarn carriers of a machine are secured to the yarn carrier rods in the same general way and the construction of all the yarn carriers of a machine is generally the same, with the exception of the angles at which the carriers are bent to approach the loop forming elements. Therefore, only one carrier rod and yarn carrier is shown and described, the so-called No. 1 yarn carrier and rod, this yarn carrier being the main yarn carrier having the greatest degree of bend with respect to the loop forming elements.

Referring to Fig. 1 of the drawing, a portion of a carrier rod indicated at 10 extends parallel to the rows of knitting needles of the knitting sections and carries a yarn laying means or carrier 12 for each of said knitting sections. The carrier 12 is secured to the carrier rod 10 and extends forwardly and downwardly to a position above a portion of the knitting or loop forming mechanism of the machine. As shown, said mechanism comprises a sinker-head 14 for each knitting section of the machine and the sinker-head includes a base member 15 and a cap member 16, both having slots or tricks therein for guiding sinkers 18 and dividers 19 by which the yarn is kinked around the stems of needles 21 during the formation of loops. Needles 21 are shown as having beards 22 for engaging the yarn to draw the new loops through the old ones to form new courses. At the time the yarn is laid by the carrier 12, the needles are at the highest points in their paths, as shown in Fig. 1, and form a recess with the sinker-head into which the yarn carrier must project

so that the yarn may be caught by the throats 24 at the forward ends of the sinkers and dividers at the times the sinkers and dividers are to kink the yarn. In the lower end of the carrier is a yarn guide or delivery tube 26, Fig. 2, the lower end of which is at a level such that yarn delivered thereby is caught by the upper edge of the sinkers.

The illustrated yarn laying means or carrier 12 comprises a holder or plate member 28 which is connected to bar 10 by means of screws 30 and may be assumed to be the main carrier having the greatest degree of bend. The yarn carrier shown is composed of an elongated member or arm 32 having a main portion adapted for mounting upon the holder 28 and a portion at its lower end arranged to position the yarn guide tube properly with respect to the loop forming elements. Means, comprising screws 34 and 20 suitably apertured portions of the holder 28 and arm or finger 32, are utilized to disconnectably attach said arm to the holder. A combined eyelet and washer plate 36 is shown assembled upon the top of the arm by the screws 34. Just 25 beyond the upper edge of the sinker-head cap 16, arm 32 bends downwardly as at 33, to lie parallel to the front face of cap member 16, the resulting inclination of the portion of arm 32 below bend 33 being best shown in Fig. 2. 30 The end portion of carrier 32 below bend 33 has a longitudinally bisecting recess or bore 35 therein to mount the yarn guide tube 26 at the lower end of the carrier. Tube 26 is so positioned that it extends below the upper edges of sinkers 18 35 in the usual manner. The dividers 19, however, are notched at their forward ends so that the carrier can be brought to a stop in the vertical plane of any of the dividers and the sinkers and dividers brought forward without danger of interfering with the tube 26 when it is necessary for the sinkers and dividers to be brought forward either for kinking the yarn between the needles or, at a later point in the cycle, to strip the loops down on the needles in the usual manner.

The tube 26 is shown as of the readily replaceable type, although the invention is not limited to this, it having been the common practice for a long period to solder the yarn guide or delivery tubes in bores in the ends of the carrier arms. As shown in Fig. 2, the tube 26 has an enlarged head 40 a portion of which extends through an aperture in the arm 32 to maintain the tube in position in the arm. A band type spring 42 is provided which lies in a groove extending across the front of arm 32 and around the edges of the arm to the rear thereof where the ends of the spring are held in recesses permitting a limited movement of the band, whereby the head 40 may be released from engagement with the arm when it is desired to remove the tube from the arm for replacement.

A knitting yarn 43 is shown as passing along the top of the carrier 12 and as being guided in a known way in holes in a turned up portion 44 on plate 28 and in holes in turned up ends 45 on washer plate 36 before reaching the upper or intake end of the opening in the tube 26. It has been customary to form a groove 46 in the arm 32 extending from above bend 33 to the head 40 of the tube 26 as shown in Fig. 2, for guiding the yarn into the tube. Now that readily replaceable tubes of the type of tube 26 are in use, the groove 46 is also necessary in that it facilitates removal 70 of tubes which cannot be drawn downwardly

5

through the end of arm 32 and which must therefore be inserted and removed through the groove.

It is in connection with the groove 46 that the difficulty of roughening and cutting has occurred. Heretofore, the yarn has passed through a portion of the groove, over the bottom of the groove at the bend 33 in the arm 32 and into the tube 26, and where the carrier was employed as the main carrier there was always some wear at the bottom of the groove. However, with the comparatively new developments in synthetic yarns, such as nylon, and particularly the finer size yarns of this type which are made of a single filament, the continuous rubbing of the yarn over the bent portion of the carrier wears or cuts a groove entirely through the carrier in a very short time. In accordance with the invention, means is provided whereby the yarn is prevented from entering any but a portion of the groove 46 and is prevented from contacting any portion of the bottom surface of the groove 46. As shown in Figs. 1, 2 and 3, there is a resilient wire-like guard or bridge member 50 attached to arm 32 in a recess 51 substantially the same height as the upper surface of the arm and extending across the groove 46 above but adjacent bend 33, although the invention is not limited to said relation of the member to the surface of the carrier in all cases. As shown in Fig. 2 the upper surface of the member 50 directs the yarn 43 substantially coaxially of the tube 26. As further shown in Fig. 3 of the drawing the member 50 has end portions 52 bent relative to the central or body portion thereof, the ends extending slightly toward each other in such manner as to engage the sides of apertures 54 in the arm 32 with a clamping action. Due to its natural resiliency, the ends 52 of member 50 may be readily removed or inserted in apertures 54 in arm 32 to replace the member when it is worn or to facilitate the removal and replacement of a tube 26. Preferably, the material of member 50 is of a hard character, but this is not essential because of its replaceability.

The yarn 43 is shown in Fig. 2 as being under tension and it will be understood that this is the normal condition of the yarn when it is being fed to the knitting elements. Therefore, the hole in the lower turned up portion 45 being above the surface of arm 32 and the upper surface of member 50 being at least close to the surface of member 32, the taut yarn 43 passes from portion 45 to member 50 along a line tangent to the upper surface of member 50. After bending around an arcuate portion of the surface of member 50, the yarn passes straight into the mouth of tube 26 without contact with arm 32 except such as is caused by whipping of the yarn. Thus it will be clear from the drawing that guard 50 substantially prevents contact of the yarn 43 with the bottom and sides of groove 46 and with the face of carrier 32, except in case the yarn whips laterally beyond ends 52. In such a case, smooth rounded shoulders 56 joining the ends 52 and the central or body portion of guard 50 effectively prevent the yarn from catching on the guard. This is especially important when the low twist multi-filament yarns are used. While such multi-filament yarns do not usually have the severe abrasive action of the mono-filament yarns it may be desirable and in some instances necessary to employ the bridge member 50 to prevent any yarn from entering the groove 46 in an arm 32, particularly where the surface in the groove has been marred by the action of previously used yarns.

It will be seen further that the member 50,

6

being formed of a round wire, presents a curved surface to the yarn in the vertical plane through the yarn when it is in its average position central of the width of arm 32 and the length of guard 50. As the yarn bends around guard 50 as it moves toward the upper end of tube 26, it is desirable that the guard be placed so that its upper curved surface is substantially tangent to the lower element of the bore of the tube 26 and it will be seen that the holes 54 are so placed lengthwise of the arm 32 that the surface of the guard and the bore of tube 26 will have the desired relationship.

In machines where a plurality of main yarns are employed in alternation as in the so-called "ringless" system, the yarn carriers for each of the plurality of yarns operate in paths, one above the other. As the "ringless" carriers are usually the closest to the cap member 16 of the sinker-head 14, the carriers have very little space between them. Therefore the top of the bridge members, while being substantially flush with the upper surface of these carriers, raises the yarn above the top face of the carriers to such an extent as to sometimes cause a carrier in one path to interfere with the yarn of the carrier in the path immediately below.

In order to avoid such interference a modified form of bridge member is employed as shown in Figs. 4 and 5. This bridge member, indicated at 60, extends across the groove 46 in the arm 32 in the same manner as the member 50. However, where the member 50 forms a substantially flat surface transversely of the arm 32, the member 60 is bent to form a concave surface 61, for the yarn, also extending transversely of the arm 32. The body portion of the member 60 is joined by rounded portions 63 to end portions 64 which are bent to engage the sides of apertures 65 in the arm 32 with a clamping action in the same manner as the ends 52 of member 50 engage the sides of apertures 54. As shown in Fig. 4, the arm is provided with a slot 68 curved to receive the body portion of the member 60 the slot being of such depth that the top edges of the member at the end portions 63 will be substantially the same height as the top surface of the arm 32 to thereby avoid interference between the carriers of the "ringless" system. It will be further seen from Fig. 4 that the member 60 is bent to such depth that the yarn will be entirely below the rounded portions 63 of the member during feeding of the yarn which will also eliminate interference between the feeding yarn and the idle carriers of said "ringless" system.

Of course, the improvements specifically shown and described by which the above desired results may be obtained can be changed and modified in various ways without departing from the invention herein disclosed and hereinafter claimed.

I claim:

1. The combination of a carrier for feeding yarn to the loop forming elements of a weft knitting machine and having a recess at one end for receiving a yarn delivery tube and having also a groove in the face thereof along which the yarn passes to said tube and through the lower end of which the yarn may enter the tube, and a wire bridge extending transversely across said groove, the carrier having holes on opposite sides of the groove into which the ends of the bridge enter and said ends biased toward each other to engage the walls of said holes.
2. The combination of a carrier for feeding

yarn to loop forming elements of a knitting ma-

chine having a recess at one end for receiving a yarn delivery tube and a groove in the face thereof along which the yarn passes to the delivery tube, and an elongated member providing a straight surface and extending transversely across the groove for preventing the yarn from engaging the bottom surface of said groove during feeding movements of the yarn, said member adapted to replaceably engage the carrier at opposite sides of the groove.

3. A carrier for feeding yarn to the loop forming elements of a knitting machine, the carrier comprising an arm having a main portion and an end portion lying at an angle to the main portion, a yarn guide tube carried by the end portion, a groove extending longitudinally of the arm, and wire means extending transversely of the groove adjacent the juncture of said main and end portions and positioned to underlie the yarn and to elevate it above the bottom of the groove and direct it into said tube.

4. A carrier for feeding yarn to the loop forming elements of a knitting machine, the carrier comprising an arm having a main portion and an end portion lying at an angle to the main portion, a groove extending longitudinally of the carrier, wire means extending transversely of the groove adjacent the juncture of said main and end portions and positioned to underlie the yarn and elevate it above the bottom of the groove and direct it into said tube, and means detachably securing said wire means to said arm.

5. A carrier for feeding yarn to the loop forming elements of a knitting machine, the carrier comprising an arm having a main portion and an end portion lying at an angle to the main portion, a yarn guide tube carried by the end portion, a groove extending longitudinally of the arm, and means extending across the groove and forming a support for the yarn not substantially higher than the adjacent upper surface of the

arm, said means being positioned to elevate the yarn above the bottom of the groove and to direct it into said tube.

6. A carrier for feeding yarn to the loop forming elements of a knitting machine, the carrier comprising an arm having a main portion and an end portion lying at an angle to the main portion, a yarn guide tube carried by said end portion, a groove extending longitudinally of the arm and means extending across the groove and forming a support for the yarn below the adjacent upper surface of the arm, said means lying adjacent the juncture of said main and end portions and positioned to elevate the yarn above the bottom of the groove and to direct it into said tube.

7. A carrier for feeding yarn to the loop forming elements of a knitting machine, the carrier comprising an arm having a main portion and an end portion lying at an angle to the main portion, a yarn guide tube carried by said end portion, a groove extending longitudinally of the arm, means detachably secured to the arm and extending across the groove and forming a support for the yarn not substantially higher than the adjacent upper surface of the arm, said means lying adjacent the juncture of said main and end portions and positioned to elevate the yarn above the bottom of the groove and to deliver it into said tube.
